Elizabeth S. Brown.

UNITED STATES PATENT OFFICE.

HENRY GOWER HOSE, OF BROOKLYN, NEW YORK.

TOY.

Application filed January 7, 1928. Serial No. 245,240.

My invention relates to a device particularly adapted for a toy for children, but also as a game for older people, and specifically to that form of such device in which a series 5 of supports is provided, toward which rings or other objects capable of being lodged upon said supports are thrown, the game consisting in throwing the rings toward the supports in such a manner as to effect lodgement 10 upon the same.

One of the principal objects of the invention is to provide a simple and easily operated toy or game of the character described, which shall be capable of economical manufacture. Further objects and advantages of 15 the invention will be in part set forth in the following specification and in part will be obvious therefrom without being specifically pointed out, the same being realized and attained by means of the instrumentalities and 20 combinations pointed out in the claims hereof.

With the above and other objects of the invention in view, the invention consists in 25 the novel construction, arrangement and combination of various devices, elements and parts, as set forth in the claims hereof, one embodiment of the same being illustrated in the accompanying drawings and described in this 30 specification.

In the accompanying drawings,

Fig. 1 is a perspective view of a device embodying my invention, showing the same assembled in position for use;

Fig. 2 is a view of such a device showing 35 the arms folded down flat without the necessity of disassembling and in a position for storing or packing; the supporting legs being removed and laid over on the body of the device;

Fig. 3 is an end view of the device in the position shown in Fig. 2, not showing, however, the legs; and

Fig. 4 is a sectional view of Fig. 1 along the line 4—4.

In carrying the invention into effect in the embodiment thereof which has been selected for illustration in the accompanying drawings and for description in this specification, 50 I provide a member 11, which may be of any suitable size or shape, but which I prefer to make substantially as shown in Fig. 1 of the drawings, and I provide supporting legs therefor 12, each having a foot 13 adapted to hold same in an upright position. Referring

to Fig. 2 it will be seen that each leg has at its upper end a pin 19 which is adapted to enter a co-acting socket in the member 11, whereby the parts when assembled are in the form shown in Fig. 1. The member 11 is provided with recesses 16 extending about half-way up from the lower edge of the member 11. 60

Referring to Fig. 2, which shows the rear side of the member 11, it will be seen that a series of eyes 20 are provided, through which 65 is inserted a rod 17; this construction is also shown in Figs. 3 and 4.

I provide a series of arms 14 adapted to receive and support devices, such as rings 15, which may be thrown at such arms. These 70 arms are pivotally supported on the rod 17, as will be clear from Fig. 2. Each of these arms is provided at its rear end with a counterweight 18, which is of such weight proportionately to the part of said arms forward of 75 the pivotal support 17 as to cause each of said arms normally to occupy a position shown in Fig. 1 but more particularly in Fig. 4, in which the forward end is considerably above the rear end. The counterweights 80 18 are preferably not equal in weight to each other, but are of different weights whereby certain predetermined arms 14 are more resistant to depression into the position shown at the right hand in Fig. 1 than are other of 85 said arms.

In connection with the apparatus above described, there may be employed devices adapted to be thrown towards the arms 14 and to be caught thereby, such as rings 15, 90 as shown in Figs. 1 and 4 of the drawings. In Fig. 1, on the second arm from the left of the figure, there is shown a ring which has found a secure lodgment on one of the arms, whereas at the right-hand of Fig. 1 95 there is shown a ring which has secured only a partial lodgment on the arm located at that part of the device, but being near the outer end of the arm, the weight of the ring has overbalanced the counterweight 18 so that the 100 arm has been drawn into the release position and the ring is about to drop therefrom.

If desired, there may be placed upon the member 11 above the various slots 16, figures indicating the number of points which a 105 player is entitled to receive by placing a ring upon the particular arm corresponding to the particular set of figures.

The operation of my invention is as follows: The player or players, being provided 110

with rings 15 or similar devices, stand at a suitable distance from the device and throw the rings toward the same, in the effort to cause said rings to become lodged upon the 5 forwardly extending arms 14. Every ring which does not find a lodgment upon an arm merely falls to the ground and is not counted. If a ring is fairly and squarely thrown upon 10 one of the arms, it will occupy the position shown on the left-hand in Fig. 1, and in that case the player throwing same is entitled to the number of points which is indicated on the member 11 above the arm upon which his ring is lodged. If a ring is not thrown fairly 15 and squarely upon an arm, but merely becomes engaged with the outer end of the arm, as shown at the right-hand in Fig. 1, the ring will probably not slide down the arm backward into the position shown by the other 20 ring, but will, on account of the greater leverage then brought into play, depress the arm 14 against the action of the counterweight 18 into the position shown on the right hand in Fig. 1, whereupon the ring slides off and falls 25 to the ground and is not counted.

Some of the arms having a much lighter counterweight than others, makes them easier to depress into the ring-discharging position, and it is therefore obviously more difficult to 30 cause a ring to find secure lodgment on a light counterweighted than upon a heavily counterweighted arm, and such light counterweighted arms are therefore given a higher credit value than the heavily counterweighted arms, as for 35 instance the middle arm of the series, upon which, if a ring is securely lodged, the player receives a credit of 1000 points. This is because the said middle arm is very lightly counterweighted, as will be seen by Fig. 2, 40 where the counterweight is shown very short, so that said arm is comparatively delicate to the touch and very easily depressed, so that a ring will slide off the same unless it is fairly lodged clear back against the member 11.

The advantages of my invention are that it provides a simple but entertaining game for young and old alike, which can be played either indoors or outdoors, and which is of a compact and durable construction, besides being easily assembled and disassembled for 50 packing and transportation.

I do not limit myself to the particular details of construction set forth in the foregoing specification and illustrated in the accompanying drawings, as the same refer to and embody only one embodiment of the invention and it is obvious that the same may be modified, within the scope of the appended claims, without departing from the spirit 55 and scope of the invention. For instance, instead of providing separate and distinct counterweights 18 for the rear ends of the arms 14, the said arms themselves may be of different lengths, or may be pivoted at dif-

ferent points upon the rod 17, so as to afford 65 a varying degree of stability.

Under some circumstances it may be considered desirable to have the counterweights on the arms 14 adjustable so as to increase or decrease the stability. This can be course be 70 done in various way, which will be obvious to those skilled in the art, as for instance by mounting such counterweights slidably on the arms and adjusting the same by means of a set-screw or similar device. 75

It is also obvious that the supporting frame of my device need not be of exactly the form shown in the drawings and hereinabove described. For instance, instead of the recess 16, a mere opening through the member 11 may 80 be provided, in which the swinging arm 14 may be pivoted, the opening being elongated sufficiently to permit the swing of the arm. If desired, this supporting frame may even be simplified to an extreme degree by providing 85 a wire frame-work for the support of the swinging arms, upon which they may be pivotally mounted in any desired manner, the said frame-work being provided with a stop of some suitable construction to hold the 90 swinging arms in the desired position to receive the rings thrown thereon.

Having thus described my invention, what I claim as new and desire to secure by Letters Patent is as follows:

1. In a game device, the combination with a supporting frame, of a plurality of arms pivotally supported on said frame, said arms being balanced upon said frame so that each arm will normally lie at a predetermined 100 angle to the vertical and being adapted to be moved out of said angle and into another position, said arms being balanced respectively in such manner that one of said arms is more easily depressed than another of said 105 arms.

2. In a game device, the combination with a frame, of an arm pivotally supported on said frame, said arm being provided with a counterweight at its rear end whereby said 110 arm is normally held in a predetermined position, but being adapted to be moved into another predetermined position, said counterweight being adjustable longitudinally of said arm.

3. In a game device, the combination with a supporting frame, of an arm pivotally secured thereto adapted to normally lie at an upward predetermined angle to the vertical when the device is in operation and adapted 120 to swing back of the supporting frame so as to lie flat against the same when the device is out of operation thereby economizing packing and storage space.

In witness whereof I have hereunto signed my name this 4th day of January 1928.

HENRY GOWER HOSE.
